UNITED STATES PATENT OFFICE.

CONRAD J. NILL, OF ERIE, PENNSYLVANIA, ASSIGNOR TO ERNST R. BEHREND, OF ERIE, PENNSYLVANIA.

PRESS MECHANISM.

1,203,039.

Specification of Letters Patent.

Patented Oct. 31, 1916.

Application filed July 22, 1915. Serial No. 41,344.

To all whom it may concern:

Be it known that I, CONRAD J. NILL, a citizen of the United States, residing at Erie, in the county of Erie and State of Pennsylvania, have invented certain new and useful improvements in Press Mechanism; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to presses, and has for its object the construction of a press mechanism suitable for pressing wet fibrous material to prepare it for fuel.

20 My invention relates more particularly to apparatus for use in a paper mill wherein paper is manufactured from wood pulp.

In the manufacture of wood pulp paper the bark is first removed from the pulp wood by first soaking or steaming the pulp wood 25 until the bark is soft when the bark can be easily removed. The bark is then so full of water that it cannot be burned under steam boilers, and prior to my invention such bark was stacked up in piles and rapidly became 30 a great nuisance and was of no use whatever. By means of my invention, however, the excess water can be rapidly pressed out of the bark and the same can be then utilized as fuel under the numerous steam boilers with which all paper mills are equipped.

The features of my invention are herein-after fully explained and pointed out, and are illustrated in the accompanying drawings in which:

40 Figure 1, is a right hand side elevation of my improved bark press. Fig. 2, is a central longitudinal section of the same. Fig. 3, is a left hand side elevation of the same. Fig. 4, is a top or plan view.

45 In these drawings, A, indicates the right hand, and A', indicates the left hand base beams of the machine, each of which is preferably composed of two channel beams positioned with their flat or plain sides adjacent. Inserted between the channel beams of each of the base beams, A and A', are upright posts of channel iron, B, B, and B', B', which are secured by means of bolts or rivets, b. Upon the upper ends of the 50 upright posts, B, B, and B', B', are second

top beams, C, C, each composed of two channel beams secured with their flat sides against the upper ends of the upright posts, B, B, and B', B', by means of bolts or rivets, b', b', so that said channel beams composing the top beams, C, C, have spaces, c, between them as shown in Fig. 4.

Upon the base beams, A and A', between the upright posts, B, B, and B', B', are placed journal bearings, D, (see Fig. 1) 65 which support journals, d, of large rollers, D', D'. On the left-hand journals of the rollers, D', D', I secure spur-gear wheels, E, E, for the purpose of driving the rollers, D', D'. Mounted in suitable bearings, F, 70 upon the base beams, A, A', is a shaft, F', upon which shaft I secure a gear pinion, F², which intermeshes with the spur-gear wheels, E, E, as shown in Figs. 3 and 4. Upon the opposite end of the shaft, F', I 75 place preferably a sprocket wheel, F³, upon which I place a driving chain, F⁴, which extends to some suitable source of power (not shown). I also provide suitable clutch mechanism, G, and clutch operating lever, G', by means of which the operation of the press mechanism may be stopped if desired. Inside of the upright posts, B, B, and B', B', I place guide beams, H, H, which are supported by means of brackets, h, which are secured to said upright posts by means of bolts or rivets, h', (see Figs. 2 and 4). Upon the opposite ends of the base beams, A and A', I mount shafts, J and J', by means of journal bearings, j and j'. The 85 shafts, J and J', support wheels or drums, K, K, and extend upwardly between the guide beams, H, H. Upon the wheels or drums, K, K, I place an endless flexible conveyor, L, which has openings, l, therethrough 90 (see Fig. 4) which will permit water to flow downwardly therethrough. In practice I preferably use the usual form of chain grate, as shown in the drawings. The conveyor, L, travels from left to right over the rollers, D', D'. To prevent the conveyor from sagging between the rollers, D', D', and between the said rollers and the drums, K, K, I secure supporting bars, L', L', L', upon the inside faces of the guide beams, H, H, 100 as shown in Fig. 2, upon which the edges of the conveyor, L, rest.

Upon the shaft, J', I secure a sprocket wheel, J², and upon one of the journals, d, of the nearest roller, D', I secure a sprocket 110

wheel J^3 , upon which I place a chain, J^4 , for the purpose of propelling the conveyer, L . Above the rollers, D' , D' , I place rollers, M , M , which rest upon the conveyer, L , with the journals, m , thereof projecting outwardly between the upright posts, B , B , and B' , B' . Slidably secured between said upright posts, B , B , and B' , B' , are journal bearing blocks, m' , which rest upon the 10 roller journals, m , m , and are provided with extensions (shown in broken lines in Fig. 1,) which engage the side of the upright posts and serve to guide said journal bearings, m' , in their vertical movement. Secured to the journal bearing blocks, m' , are vertical bars, N , which extend upwardly through the space, c , between the members of the upper beams, C , C , as shown in Figs. 1, 2 and 3. To the upper beams, C , C , I secure upright bars, N' , to which are pivoted levers, N^2 , which levers are also pivoted to the upright bars, N . On the sides of the machine frame I pivot weighted levers, O , O , by means of pivots, o , o , and to the free 20 ends of the levers N^2 , bars, O' , extend downwardly, and are pivoted to the weighted levers, O , by means of pivots, o' , so that the action of the weights, O^2 , is communicated to upright bars, N , to press the journal bearing blocks, m' , down upon the journals of the rollers, M . The journal bearing blocks m' , at each end of the rollers M , and the weighted lever mechanism associated with each of said blocks m' being entirely disconnected with the journal bearing block at the opposite end of each roller M , as shown in Figs. 2 and 4, of the drawings, are free to be raised and lowered independently of the blocks, m' , at the opposite end of each 30 roller, as either end of each roller M , is raised or lowered by the varying thickness of the layer of material carried thereunder by the chain conveyer L , so that during the operation of the machine, hereinafter described, each end of each roller M , is free to rise and lower independently of the opposite end thereof, and the journal bearing blocks m' , resting upon each of said roller journals m are thereby caused to slide upwardly between the guide posts B' , B' , and as each journal m , moves downward, the weighted levers O , through their connecting mechanism N , N^2 and O' , cause the journal bearing blocks m' , to follow downward and remain in engagement with the roller journals m , thereby keeping the rollers M , in vertical alignment with the lower rollers D' . In order to cause the material placed upon the conveyer, L , to be spread evenly over the width 40 thereof, I mount upon the guide beams, H , H , in suitable slideways P , a transverse slide-bar, P' , which is provided with fingers, P^2 , (as shown in Figs. 2 and 4), which fingers bend downwardly somewhat so as to rake the material as it is carried toward the

rollers by the conveyer, L . To cause the slide-bar, P' , to reciprocate in the slideways, P , I provide a rock shaft, Q , which is mounted in a bracket, Q' , secured to one of the guide beams, H , (see Figs. 3 and 4) and 50 in a suitable bearing, Q^2 , on the base beam, A' . This rock shaft, Q , is provided at its upper end with an arm, q , which is connected with the slide-bar, P' , by means of a link, q' , (see Fig. 4). The rock-shaft, Q , is 55 also provided with an arm, R . Upon the end of the shaft, F' , I fix a wrist pin, R' , which is eccentric to said shaft, and extending from said wrist pin, R' , to the arm R , on the rock-shaft, Q , is a rod or bar, S , 60 which, as the shaft, F' , revolves, causes the rock-shaft, Q , to rock in its bearings, and, through the arm, q , and link, q' , the slide-bar and its fingers, P^2 , are caused to reciprocate transversely over the conveyer, L . 65

Upon the intake end of the guide-beams, F , I place a flat plate, T , to prevent material from being placed upon the conveyer until it has flattened out after passing around the drum.

In operation the driving belt or chain, F^4 , causes the wheel, F^3 , shaft, F' , and pinion, F^2 , to rotate in the direction of the arrow on the wheel, F^3 , in Fig. 1, which through the spur gear wheels, E , rotates the lower 70 rollers, D' , in the direction of the arrow on the wheel, J^3 , which through the chain, J^4 , and wheel, J^2 , causes the conveyer, L , to travel between the lower rollers, D , and the upper rollers, M , in the direction of the arrow on the plate, T , in Fig. 4, so that, 75 when material to be pressed is placed upon the conveyer, L , it is thereby carried under the rollers, M , which roll over it and press out the surplus water, which flows through the conveyer, L , and is carried away in any suitable manner, (not shown). Meanwhile the slide-bar, P' , being actuated as hereinbefore described, causes the fingers, P^2 , to level the material into a uniform layer upon 80 the conveyer before it passes under the rollers, M , which rollers, as the layer of material varies in thickness, rise and lower, during which the weighted levers, O , through 85 their intermediate connections act to maintain the journal bearing blocks, m' , down upon the journals, m , of the rollers, M . It will be seen from the foregoing that the operation of my press mechanism is continuous, and that after the same is in motion 90 all that is necessary is to deposit the material to be pressed upon the conveyer, L , and remove the pressed material as it falls from the discharge end of the machine.

Having thus fully shown and described 95 my invention so as to enable others to construct and utilize the same, what I claim as new and desire to secure by Letters Patent is:

1. In a continuous press mechanism the combination of a lower supporting roller 100

mounted in a permanent horizontal position, a continuous flat chain conveyer traveling thereon in unison with the rotation thereof, an upper roller resting upon said chain conveyer above said supporting roller and receiving its rotary motion from said chain conveyer, axial journals on said upper roller, upright guide posts at each side of said axial journals adapted to maintain said upper roller in the same vertical plane with said lower roller whereby each end of said upper roller is permitted to be raised and lowered by the varying thickness of material carried thereunder by said conveyer, substantially as and for the purpose set forth.

2. In a continuous press mechanism, the combination of a lower supporting roll, a continuous flat chain conveyer traveling thereon and in unison therewith, an upper press roller resting upon said chain conveyer and receiving its rotary motion therefrom, journals on said upper roller, upright guide posts at each side of said journals, journal bearing blocks having semi-cylindrical recesses in their under sides to receive said journals thereinto, slidably mounted between said upright guide-posts, whereby said upper roller is maintained in the same vertical plane as the lower roller, while said upper roller or each end thereof, independently of the opposite end, is permitted to be raised or lowered by the varying thickness of material carried thereunder by said conveyer, substantially as and for the purpose set forth.

3. In a continuous press mechanism, the combination of base-beams, journal bearings secured thereon, a lower roller, journals on said roller mounted in said bearings, a spur-gear wheel on one of said roller journals, a drive shaft mounted in bearings on said base-beams, a gear-pinion thereon intermeshing with said spur-gear, an endless flat chain conveyer above said lower roller, mechanism actuated by said roller to cause said conveyer to travel over said roller in unison therewith, upright posts secured to said base-beams at side of said roller, a press roller above said lower roller resting upon

said conveyer and receiving its rotary motion from said conveyer, journals on the ends of said upper press roller projecting between said upright posts, journal bearing blocks having semi-cylindrical recesses in their under sides slidably mounted between said upright posts and resting upon said journals and weighted lever mechanism adapted to press downward on said journal-bearing blocks, whereby said upper roller is maintained in the same vertical plane as the lower roller, while said upper roller, or each end thereof independently of the opposite end, is permitted to be raised or lowered by the varying thickness of material carried thereunder by said conveyer, substantially as and for the purpose set forth.

4. In a machine of the class described, the combination of base-beams, journal bearings secured thereon, a lower roller, journals on said roller mounted in said journal bearings, rotatable drums mounted upon the ends of said base-beams, an endless flat chain-grate around said drums and over said roller, upright guide-posts secured on said base-beams at each side of said roller, guide-beams between said upright posts and the edges of said chain-grate, means on said guide-beams to prevent said chain-grate from sagging, mechanism to cause said roller to rotate and said chain-grate to travel in unison therewith, a press roller above said lower roller and resting upon said chain-grate, and receiving its rotation therefrom, journals on the ends of said upper roller, journal bearing blocks having semi-cylindrical recesses in their under sides, resting upon said upper roller journals and slidably mounted between said upright guide-posts, whereby said upper roller is maintained in the vertical plane of said lower roller while said upper roller, or each end thereof independently of the opposite end, may be raised or lowered by the varying thickness of material carried thereunder by said conveyer, substantially as and for the purpose set forth.

In testimony whereof I affix my signature.

CONRAD J. NILL.
